UNITED STATES PATENT OFFICE.

AXEL H. HELANDER, OF PUEBLO, COLORADO.

METHOD OF REDUCING METAL-BEARING MATERIALS.

No. 831,967.

Specification of Letters Patent.

Patented Sept. 18, 1906.

Application filed December 26, 1905. Serial No. 293,414.

To all whom it may concern:

Be it known that I, AXEL H. HELANDER, a citizen of the United States, residing at Pueblo, in the county of Pueblo and State of Colorado, have invented certain new and useful Improvements in Methods of Reducing Metal-Bearing Materials, of which the following is a specification.

This invention relates to a method of reducing flue-dust, fine ores, and concentrates and of introducing the same into a furnace to accomplish such reduction.

My method consists in mixing the fine metallic oxides, ores, or concentrates with liquid or semiliquid material, preferably one containing fuel values, to which mixture may also be added finely-divided solid fuel, such as coke-breeze, together with fluxing material. The moistening materials may comprise tar, oil, or other liquid or semiliquid substances containing carbon, and the mixing may precede or be coincident with the introduction of the plastic or viscous mass into the blast-furnace. For example, the mixed materials may be charged in the form of a paste or balls with the other burden in the usual manner, may be injected by a pump, "notch-gun," or "mud-gun" at about the level of the furnace-mantle, or the solid and liquid particles may be supplied from separate sources, mixed at the injecting-nozzles, and driven into the furnace by a blast sufficiently strong to overcome the inside pressure of the furnace, the object being in every case to supply the mixed material in such condition as to prevent its being carried out of the furnace, unreduced, by the air-blast. In whatever manner introduced the material will melt and begin to reduce to the metallic form soon after entering the furnace, thus solidifying to such an extent as not to be carried out at the top of the furnace.

If injected either above or below the mantle, the mixed materials are preferably supplied through a plurality of nozzles spaced equally around the furnace, such nozzles being of refractory material or of metal, with water-cooling jackets of any well-known form.

By the term "viscous mixture," as used in the claims, I mean a mixture having such a degree of viscosity or plasticity as not to be capable of retaining its shape for a prolonged period of time, such as would be necessary in molding and charging the same in the shape of bricks or blocks.

All apparatus for carrying out my method is well known in metallurgy, and it is not deemed necessary to further describe or illustrate it.

Many changes may be made in such apparatus, the method of mixing, and the proportions of the metal-bearing, fuel-bearing, and fluxing materials without departing from my invention, since

What I claim is—

1. The method herein described of reducing metal-bearing materials, which consists in forming a viscous mixture thereof with fuel-bearing material and injecting said mixture into a reducing-furnace; substantially as described.

2. The method herein described of reducing metal-bearing materials, which consists in forming a viscous mixture thereof with fuel-bearing material and introducing said mixture into a blast-furnace at or above the zone of fusion; substantially as described.

3. The method herein described of reducing metal-bearing materials, which consists in forming a viscous mixture thereof with fuel-bearing and fluxing materials and injecting said viscous mixture into a blast-furnace at substantially the zone of fusion, substantially as described.

4. The method herein described of reducing metal-bearing materials which consists in simultaneously forming and injecting into a reducing-furnace a viscous mixture of metal-bearing and fuel-bearing materials; substantially as described.

In testimony whereof I affix my signature in presence of two witnesses.

AXEL H. HELANDER.

Witnesses:

W. EDWARD BERG,
JOHN F. BIRD.
